UNITED STATES PATENT OFFICE.

WILLIAM A. EDWARDS, OF BARTLETT, ILLINOIS.

METHOD OF SUPPLYING A COMBUSTIBLE MIXTURE TO INTERNAL-COMBUSTION MOTORS.

Application filed November 13, 1920. Serial No. 423,987.

This invention relates in general to internal combustion motors, and has more particular reference to a method of supplying a combustible mixture to the cylinders there-
5 of.

My method contemplates the production at or near the fuel supply tank which is customarily mounted on the rear of an automobile, of a mixture of fuel and air, which 10 mixture is then conducted as such to a point in proximity to the engine where it is reduced in richness by the admixture therewith of a sufficient amount of air to meet the requirements of the engine at the speed 15 at which it may be running. The initial mixture at the tank is of substantially uniform richness for low speeds of the engine and is of proper proportions to enable the engine to idle without the admixture there-
20 with of additional air. Furthermore my invention also breaks up and highly atomizes the fuel at the tank producing a relatively homogeneous mixture at that point which becomes further broken and homogenized 25 during its travel over relatively long horizontal distance through a relatively small diametered conduit, due to the frequency of the repeated impacts of the minute liquid globules which are carried in suspension in the air current, against the conduit wall, occurring due to the vibration of the current 30 which results from the friction, the mixture becomes, to an appreciable extent, vaporized en route thus augmenting its combustibility 35 and efficiency.

One of the primary purposes of my invention, therefore, is to so finely break up the fuel particles, and to so thoroughly mix them with and surround each particle by the 40 requisite amount of air for its combustion before the charge is admitted to the cylinder, that upon the production of the spark, the entire charge will explode instantaneously to exert a maximum effort against the 45 piston.

Another feature of my invention resides in the fact that in the production of a charge such as I have described, a less amount of fuel is employed than would be 50 required in an ordinary charge.

In the use of the vacuum feed systems with which automobiles are customarily equipped at the present time, the fuel is car-

ried as a liquid from the tank at the rear of the car to a receptacle located under the 55 hood and above the level of the carburetor and in aeroplanes also the fuel is conducted as a liquid to the carburetor. Leakage in the fuel line or from the receptacle not infrequently results in disastrous conflagra- 60 tions. In the use of my invention, however, the fuel is not conducted as a liquid, but on the contrary, is conducted from the rear end of the car or from the fuel supply tank wherever located as an atomized mixture of 65 fuel and air and a leak in the pipe line will not result in leakage of the liquid fuel and the collection thereof at some point where it is liable to become accidentally ignited, with disastrous results, but a leak in the line 70 can produce no worse result than the drawing of a surplus of air into the mixture delivered to the cylinders, which will render it so weak that the motor may fail to operate. All dangers of conflagration from leaky 75 lines are therefore entirely eliminated.

Other objects and many of the attendant advantages of my invention will be readily appreciated as the same becomes better understood by reference to the following de- 80 scription and the accompanying drawings, upon which one practical and preferred apparatus for carrying my method into effect, is illustrated.

Referring to the drawings:

Fig. 1 is a side elevation somewhat dia- 85 grammatical in character, of a system by means of which my improved method may be practiced;

Fig. 2 is an enlarged longitudinal section- 90 al view of the primary mixture-producing apparatus; and

Fig. 3 is a similar view of the apparatus whereby the vapor is converted into a mix- 95 ture of the required richness.

Referring now to the drawings more in detail, reference character 5 indicates generally the chassis frame of an automobile carrying at its forward end the motor 6 and, at its rear end beneath the frame, the gaso- 100 line fuel tank 7. My invention contemplates the production of a rich mixture at the tank 7, which mixture is conducted as such to a point in proximity to the motor, where it is converted, by being automatically diluted 105 with air, into a mixture of the proper pro-

portions required by the speed of the motor which is then delivered to the motor cylinders.

For the purpose of producing a rich mixture at the tank 7, I prefer to employ an apparatus such as is disclosed in Fig. 2, although other means for accomplishing this result might be substituted in lieu thereof. Referring to this figure, it will be observed that I have mounted on the top of the tank, an outstanding collar or ring 8, into which is threaded a plug or block 9 equipped with a depending tube 11, which is projected downwardly into the tank through an opening in the top thereof to a point near the bottom of the tank. This plug 9 is threaded to receive a jet nozzle 12, and is also cored out to accommodate the lower end of a pipe or tube 13, which leads from the tank to a point in proximity to the motor. The tube is equipped adjacent the tip of the nozzle 12 with a venturi 14, and the lower end of the pipe 13 is provided with a series of laterally opening ports 15 disposed in registration with similarly arranged ports 16 formed in the annular walls of the plug 9. A screen may be employed, if desired, around the plug to screen the air entering into the ports 16 and 15.

It will be obvious that when suction is applied to the pipe 13, the inrush of air into this pipe through the ports 16 and 15 will produce a vacuum in the throat of the venturi 14 sufficient to raise the liquid fuel from the tank 7 through the tube 11 and cause its discharge into the throat of the venturi, where it becomes atomized by the admixture therewith of the air flowing through the venturi.

The admixture of air and liquid fuel at this point is as thorough and complete as would ordinarily be secured with a carburetor, but the fuel particles are not sufficiently finely divided or so uniformly distributed throughout the air as to produce the most efficient results in the cylinders. The rich mixture is now conducted through the long pipe 13 at relatively high velocity and the time consumed in its travel from one end of the tube 13 to the other affords an opportunity for further and finer subdivision of the fuel particles and their more uniform admixture with the air in which they are carried and in fact an appreciable vaporization of the fuel takes place during its travel through the pipe 13. The homogenizing and vaporizing action resulting from the relatively long distance through which the commingled air and fuel are in contact with each other in the pipe which is further facilitated by mechanical agitation of the mixture during its passage through the long pipe 13 resulting from friction between the rapidly traveling mixture and the surrounding walls of the pipe, in-

creases the homogeneity and uniformity of the mixture to such an extent that a much more homogeneous mixture is delivered from the pipe than was produced at the intake end of the pipe.

This mixture, which is delivered from the pipe 13, while homogeneous in character and composition, consisting of minute particles of liquid fuel, carried in suspension in the air with which it is admixed, is, however, too rich or in other words, too near the saturation point for efficient utilization in the motor except at idling speeds. My invention contemplates, therefore, the reduction of this mixture to a point suited to the motor speed requirements by admixing therewith a suitable proportion of air, which in effect, dilutes the mixture and further disintegrates the fuel particles and disperses them throughout the resultant mixture so that each minute particle is surrounded with sufficient air to support the instantaneous combustion thereof.

For the purpose of supplying this supplementary air in the requisite quantities and of thoroughly commingling the previously produced mixture with this supplementary air, I prefer to employ a device substantially similar in principle to that disclosed in Fig. 1, and on a larger scale in Fig. 3. Referring to these figures, reference character 17 designates a curved pipe or conduit, equipped at one end with a circumferential flange 18, by which the same may be attached to a pipe section 19 connecting directly with the delivery pipe 21, which discharges into the manifold 22, the pipe section 19 being preferably equipped with an ordinary throttle valve 23, adapted to be manipulated by the driver in the usual manner.

The upper end of the conduit 17 is equipped adjacent to the pipe section 19 with a venturi 24 and the vapor pipe 13 is introduced through an opening formed in the conduit 17 in alignment with this venturi, the upper end of this pipe 13 terminating in the throat of the venturi as shown in Fig. 3. Near the opposite end of the conduit 17, I have provided a series of circumferential slots 25 through which atmospheric air is drawn into the conduit by the suction of the cylinders and immediately beneath these slots, the conduit is shaped to provide a valve seat 26 against which a disc valve 27 is adapted to seat under the influence of an expansion spring 28 surrounding the stem 29 of the valve. In order to permit a free flow of air around the valve disc when withdrawn from its seat, the conduit is preferably enlarged to provide an internal groove 31, as shown in Fig. 3.

For the purpose of steadyng the action of the valve 27 so as to prevent too rapid fluctuations of the valve, the upper end of the stem 29 is provided with a piston 32 slidably

fitting within the end of the conduit, which is closed by a cap 33 threaded thereon, thus producing in effect a dash-pot, which steadies the opening and closing movements of the 5 valve. The piston 32 or the cap 33 may be provided with a small vent opening to permit movement of the piston.

When the motor is turned over, the suction produced in the intake manifold by the 10 pistons draws the rich combustible mixture produced at the rear end of the pipe 13 adjacent to the gasoline tank into the throat of the venturi 24 by which it is further homogenized, and when the motor is turning 15 over slowly, such as in starting or idling, this thoroughly homogenized but quite rich mixture is delivered directly and undiluted to the cylinders. As the motor speeds up, however, the increased suction will cause the 20 valve 27 to open an amount proportionate to the increase in vacuum in the conduit 17 so that supplementary air enters around this valve and is drawn through the venturi 24, where it is thoroughly commingled with the 25 rich mixture delivered from the pipe 13. The inflowing air around the valve 27 is drawn through the venturi 24, thereby creating a vacuum which exerts a suction on the pipe 13 to increase the flow of mixture 30 therethrough. The finely divided fuel particles of the mixture are delivered by the pipe 13 further separated one from another and diffused through and mixed with the supplementary air by the action of the 35 venturi 24, thereby producing a combustible mixture in which each minute fuel particle is surrounded by sufficient air to support its instantaneous combustion. This mixture is then delivered to the cylinders and upon the 40 production of a spark therein, an instantaneous and powerful explosion is secured which produces much more power than the successive or stratified explosions obtained with the imperfect mixture produced by an 45 ordinary carburetor. Furthermore, by obtaining a maximum efficiency from the fuel utilized, I am able to secure under actual tests, a materially increased motor horse power with the use of much less fuel than otherwise 50 used by the same motors equipped with carburetors.

It is believed that my improved method will be understood and its advantages appreciated from the foregoing without further 55 description, and it should be manifest that the apparatus for carrying my method into effect may be varied in its structural details within wide limits without exceeding the scope of the invention, as defined in the 60 following claims.

I claim:

1. A method of supplying an internal combustion engine with fuel which consists in producing at a point remote from the 65 engine a mixture of air and fuel, conduct-

ing said mixture unmodified to said engine when idling, and automatically modifying said mixture by introducing auxiliary air thereto at a point adjacent the engine in proportion to the speed thereof during the 70 operations other than idling.

2. The method of supplying an internal combustion engine with fuel which consists in admitting to a conduit at a point remote from the engine air and fuel in proportion 75 for producing a combustible mixture suitable for operating the engine under idling conditions; conveying the same through said conduit for mixing the elements, and delivering the same otherwise unmodified 80 to the engine.

3. The method of supplying an internal combustion engine with fuel which consists in creating in a conduit an extended region of low pressure by the suction of the engine; restricting the admission of air to said region and thereby creating an area of lower pressure; admitting fuel to the conduit at said area in quantity to form a combustible mixture suitable for operating the engine under idling conditions; producing at a point adjacent to the engine a second area of lower pressure; admitting air at said lower pressure area, automatically according to the engine speed, to render the 90 fuel mixture suitable to operating conditions and engine speed other than idling, and conveying said resultant mixture to the engine. 95

4. The combination with an internal combustion engine, of an apparatus for supplying a combustible mixture thereto comprising means for producing an area of low pressure, means for admitting air and fuel to said area to form a mixture of proper proportions for operating the engine, a long constricted homogenizing tube connecting the area of low pressure with the engine for delivering said mixture thereto unmodified when idling, and means for creating 100 a second area of low pressure adjacent the delivery end of the homogenizing tube and means automatically responsive to the speed 105 of the engine under operating conditions other than idling for admitting an auxiliary air supply to thereby correspondingly modify the character of the mixture. 110

5. An apparatus for supplying a combustible mixture to an internal combustion engine comprising means for producing a combustible mixture of air and fuel, means for delivering said mixture to an engine, homogenizing means connecting the mixture producing means and the mixture delivery means, said homogenizing means including 115 a long constricted tube, means for creating an area of low pressure adjacent to the delivery end of the homogenizing tube, and a valve adjacent to said delivery end of the tube arranged for opening automatically re- 120 125 130

sponsive to the speed of the engine under conditions other than idling to admit auxiliary air to said mixture to modify the character thereof in accordance with engine speed.

6. The combination with an internal combustion engine, of an apparatus for supplying a combustible mixture thereto comprising means for producing a mixture of air and fuel, a conduit for conveying the mixture to the engine unmodified as to proportions when idling, a casing surrounding the delivery end of the conduit and communicating with the engine, a valve in said casing, said valve being normally closed but operable to automatically admit auxiliary air to the casing in response to the speed of the engine under conditions other than idling, and means carried by the casing ad-

jacent the delivery end of the conduit where- 20
by the passage of said auxiliary air into the engine creates an area of low pressure at the delivery end of the conduit which functions to increase the rate of fuel supply. 25

7. An apparatus for supplying a combustible mixture to an internal combustion engine comprising means for producing a combustible mixture, a conduit for conveying the same to an engine, a Venturi tube 30 positioned adjacent to the delivery end of the conduit, and an air valve operatively associated with the Venturi tube and automatically responsive to engine speeds under engine conditions other than idling to admit 35 air to said Venturi tube whereby to vary the rate of fuel supply through the conduit.

WM. A. EDWARDS.
